UNITED STATES PATENT OFFICE.

PONTUS OSTENBERG, OF SAN JOSE, CALIFORNIA, ASSIGNOR OF ONE-HALF TO JOHN A. NAISMITH, OF SAN JOSE, CALIFORNIA.

INTERNAL-COMBUSTION ENGINE.

1,323,545.

Specification of Letters Patent.

Patented Dec. 2, 1919.

Application filed November 27, 1916. Serial No. 133,725.

To all whom it may concern.

Be it known that I, PONTUS OSTENBERG, a citizen of the United States, and resident of San Jose, in the county of Santa Clara and State of California, have invented certain new and useful Improvements in Internal-Combustion Engines, of which the following is a specification.

My invention relates to internal combustion engines, and particularly to the location of the exhaust passage or passages in the cylinder thereof.

One object of my invention is to provide an internal combustion engine that will be economical in the use of fuel. Another object is to provide an internal combustion engine that will more effectually exhaust the burnt gases than the engines now in use. Another object of my invention is to provide for the explosion of a comparatively small amount of gas mixture with a short compression stroke and thus secure a comparatively long power stroke of the piston.

With the above and other objects in view, the invention consists in the novel and useful provision, formation, construction, combination and relative arrangement of parts, members and features as hereinafter described, shown in the drawing and finally pointed out in the claims.

In the drawings:

Figure 1 is a longitudinal section through an internal combustion engine embodying my invention and in which a sleeve valve is used.

Fig. 2 is a longitudinal section through an internal combustion engine embodying my invention and in which a puppet valve is used.

Fig. 3 is a diagrammatical illustration showing one method of operating the rotary valve indicated in Fig. 1.

Fig. 4 is a diagrammatical illustration showing the operating cycle of an engine embodying my invention.

Similar characters of reference indicate similar parts throughout the several views.

Referring now more particularly to the drawings, 1 indicates the engine cylinder, 2 the crank case, 3 the water jacket, 4 the piston head, 5 a sleeve valve operated in any suitable manner as by arm 6 and eccentric 7 on shaft 8, and 9 the piston rod. Cylinder 1 is tapped at 10 for the insertion of a

spark plug. At 11 is indicated an annular passage encompassing cylinder 1 and connected to combustion chamber 12 by ori-fices 13. At 14 is shown a conduit connecting crank case 2 with passage 11 at 15. The letter "A" indicates the distance traversed by the piston head 4, and the letter "B" indicates the middle half of distance "A". In cylinder 1 and within the distance indicated by the letter "B" are positioned exhaust ports 16 and exhaust port 17, said exhaust port 17 being independently controlled by rotary valve 18, said valve 18 being operated as indicated in the diagram in Fig. 4 by arm 18^a, link 18^b, arm 18^c and carbureter valve 18^d. Sleeve valve 5 is provided with ports 13^a, 16^a and 17^a, which register with their respective ports 13, 16 and 17 at the completion of the power stroke of piston head 4, sleeve valve 5 advancing and closing said ports 13, 16 and 17 as piston head 4 advances, arm 6, eccentric 7 and piston rod 9 operating in the usual manner.

As the power stroke of piston head 4 is completed and the various ports are caused to register as above described, port 17 being closed by valve 18, a fresh supply of combustible mixture rushes into combustion chamber 12 through ports 13^a and a portion of the burnt gases exhaust through ports 16. As the incoming fresh mixture now fills chamber 12 the compression stroke of the piston head 4 drives out the remainder of the burnt gases through ports 16 and passes on to compression, ports 16 and 13 being closed by sleeve valve 5 as hereinbefore described.

The operating cycle of my improved engine is clearly illustrated in Fig. 5. In this figure "C" represents the power stroke of piston head 4, "D" that portion of the return stroke during which a fresh charge is admitted to chamber 12 and the burnt gases exhausted, and "E" that portion of the return stroke during which compression takes place. As in the sectional illustrations "A" represents the full distance traversed by the piston head 4, and "B" represents the middle half of distance "A" and within which distance point "F" is positioned thereby proportioning "D" to "E" as circumstances may require. With port 16 positioned as shown in Fig. 1, point "F" would be shown in the diagram at F'. With port 17 open point "F" would be shown in the diagram at F''. 110

When the speed of the engine is reduced and a smaller charge of fuel is being fed into chamber 12, and the carbureter valve is partially closed, the several parts are positioned 5 as indicated in dotted lines at 18', 18^a, 18^b, 18' and 18^a in Fig. 4, the rotary valve 18 being turned to the position 18' by the movement of said valve 18^a.

The efficiency of the two cycle type of engine 10 is greatly increased by the arrangement of ports above set forth because the cylinders are thoroughly cleansed by the incoming fresh charge; the burnt gases are all exhausted by the pressure of the fresh 15 charge from one direction and the advancing piston head from the other direction; and a longer time is allowed for the escape of the burnt gases.

If the engine is running slower and valve 20 18 is opened by the action of the carbureter valve, or by any other similar connection, as illustrated in Fig. 4, then the reduced supply of fresh fuel is compressed in a short compression stroke but is expanded in a long 25 power stroke because port 17^a does not register with port 17 until the power stroke is nearly completed, but when it does open the said port 17^a exhausts simultaneously with ports 16.

30 In Fig. 2 is shown how an ordinary pup-
pet valve may be used instead of the sleeve
valve described above. Exhaust port 16 is
provided with a seat 19 to receive valve 20.
Valve 20 is operated by rod 21 slidably
35 mounted in bearings 22 and in turn operated
by cam 23 on crank shaft 8, so that when the
piston head advances cam 23 closes valve 20
on seat 16 while said piston passes on to com-
pression but opens upon the completion of
40 the power stroke of said piston.

Since my invention consists essentially in
the location of the exhaust port or ports, it
is evident that any suitable form or type of
valve or valves may be used without depart-
45 ing from the spirit of my invention, and
the same may be embodied in many differ-
ent types of engines without departing from
the spirit of my invention. It is under-
stood, therefore, that I do not wish to con-

fine myself to the specific construction and 50 relative arrangement of parts and features herein shown and described, but that various changes may be made within the scope of the appended claims.

Having thus described my invention; what 55 I claim as new and desire to secure by Letters Patent, is:

1. An internal combustion engine includ-
ing a cylinder having a plurality of exhaust
ports disposed therein at varying distances 60 from the cylinder head, means coöperating
with the piston for opening or closing said
exhaust ports at predetermined intervals,
and additional means operated independ-
ently of the piston for controlling the ex- 65 haust port positioned nearest the head of
the cylinder.

2. An internal combustion engine includ-
ing a cylinder having a plurality of exhaust
ports disposed within the center half of that 70 portion thereof traversed by the explosion
end of the piston head and at varying dis-
tances from the cylinder head, means co-
operating with the piston for opening or
closing said exhaust ports at predetermined 75 intervals, and additional means operated in-
dependently of the piston for controlling the
exhaust port positioned nearest the head of
the cylinder.

3. An internal combustion engine includ-
ing a cylinder having a plurality of exhaust
ports disposed within the center half of that 80 portion of said cylinder traversed by the ex-
plosion end of the piston head and at vary-
ing distances from the cylinder head, and
a sleeve valve operatively positioned in said
cylinder and provided with ports adapted to
85 be simultaneously thrown into or out of reg-
ister with their respective exhaust ports
when said engine is in operation, and inde-
pendent means for controlling the exhaust
port positioned nearest the head of said
cylinder.

In testimony whereof I have hereunto
affixed my signature this 21st day of No- 95
vember, 1916.

PONTUS OSTENBERG.
